FOUNDATION GARMENT

Gladys W. Geissmann, New York, N.Y.

Application May 15, 1957, Serial No. 659,405

12 Claims. (Cl. 128—546)

This invention relates to foundation garments.

Foundation garments of conventional design characteristically compress the figure toward a predetermined, often stylized shape. They tend to deal with the problem of figure control without regard for the skeletal structure under the flesh or the direction and function of the principal muscles and nerve centers. Seldom are they able to accommodate such normal positions of the body as sitting, bending, kneeling, stooping, and stair-climbing without binding or painfully constricting one or more of the critical areas of the anatomy.

One object of the present invention, therefore, is to provide a foundation garment which supports and shapes the figure to achieve attractive, anatomically correct contours through a wide range of positions.

Another object of the invention is to provide a foundation garment which affords freedom of movement and posture.

Another object is to provide a foundation garment which affords a logical continuity of stresses interrelated to the changing planes around the body so that forces can be developed in localized areas where required without punishing other areas.

Another object of the invention is to provide a foundation garment in which the continuity of figure-controlling forces can be used to afford an uplift for the buttocks.

In accordance with the invention a set of shaped parts are joined with their direction of stretch assuming a predetermined pattern to achieve a sequence of graded tensions circumferentially throughout the garment. To this end a pair of arch-shaped members, cut to have the direction of stretch of the sheet material extending more or less vertically, are arranged so that the upper or arching sections rest on the hips, this section being relatively wide and flared outwardly to accommodate the slope or contour of the upper hip. Front and back limbs of the arch members depend vertically from each arched section, and resilient side panels are attached within the front and back limbs of each. Front and back panels span respectively the distances between corresponding front and back vertical limbs of the two arched members. The front and back panels preferably comprise two layers of fabric arranged with their directions of stretch at angles to each other and also at angles to the vertical.

In one preferred embodiment of the invention, the direction of stretch of the side panels slants upwardly from the rear to the front to give a natural pull across the thighs. The arch members, which ride on the natural supporting ledges of the hips, combined with the action of the several panels, impart uplift to the buttocks. If desired, the built-in contour of the hip area can be modified by the use of crescent-shaped pieces underlaid at the top edges of the side panels forming a double thickness, both edges of which are attached to the lower edge of the upper arch section, thereby to grade off from the stronger material in the upper section of the arch members to relatively more elastic side panel material. The waistband portion can take various forms depending on

2

the height or build-up required. It can, for example, be formed integrally for the most part with the front and back panels or it can be made up of a separate piece stitched to the basic garment assembly. Overall, a continuity of stress through changing planes about the body is established which affords freedom of motion as well as pleasing, natural figure contours. Uplift for the buttocks can be derived from the lifting action of the hips transmitted to the buttocks through a curving force line,

which can include a seam, passing over the hip areas and then rearwardly downwardly in the manner of a sling. Representative embodiments of the invention from which the above and other features will be understood are described below having reference to the accompanying drawing in which:

Figure 1 is a side view of a foundation garment as it would appear while being worn;

Figure 2 is a view in perspective showing, predominantly, the front position of the garment of Figure 1 and some of the left side, parts of the garment being lined to show grain or stretch direction;

Figure 3 is a back view of the garment of Figures 1 and 2;

Figure 4 is a view in perspective of the left side portion of the garment as it would appear when placed on a flat surface, illustrating in particular the built-in contours;

Figure 5 is a plan view of the left side panel including lines to illustrate direction of predominant stretch;

Figure 6 is a plan view of the pieces of which the arch members are formed;

Figure 7 is a plan view of the front panel of the garment, one layer of fabric being shown folded back to illustrate contrasting directions of stretch;

Figure 8 is a plan view of the back panel of the garment, one layer of fabric being shown folded back to illustrate contrasting directions of stretch;

Figure 9 is a plan view of a piece, including direction-of-stretch lines, which can be used as a cooperating part of the contoured side assembly; and

Figure 10 is a developed plan view of front, side and back panels of a foundation garment in which there is incorporated a built-up waistband.

Referring first to Figures 1-3 of the drawings, the invention is illustrated as embodied in a foundation garment indicated generally by the numeral 2. The garment includes a pair of side panels 3 and 3' (Figure 5) fitting within and joined to tapering arch members 4 and 4', respectively. The side panels are preferably formed from material which stretches in both warp and weft directions, the former approximately 15 to 60 percent greater, such, for example, as knitted fabrics known as power net. The predominant direction of stretch is preferably arranged in a direction sloping gently upwardly moving from the back toward the front, as shown by the sloping, parallel stretch lines in Figures 2 and 5.

The arch members include curved or arched upper sections 5 and 5' in the form of a band of greatest width at the top of the arch and flared outwardly in the sloping or oblique plane of the hips. The upper section of the arch members tapers downwardly, terminating in depending front and back limbs 6, 6' and 7, 7' respectively, the limbs also tapering downwardly to their lower ends, which can, if desired, carry garter elements 8.

The sloping contour of the arch members 4 and 4' can be achieved by the construction illustrated at Figure 6 showing the component parts 9 and 10 of one member. The parts 9 and 10 represent the front and back halves of the arch member and are cut at angles at their upper, abutted edges 11 and 12 so that they come together in a seam 13 (Figures 1 and 2) which forces the upper section of the arch into its characteristic flared shape. It

is also possible to construct the contoured arch members of three or more pieces having their respective opposing edges cut at appropriate angles to impart the outwardly flaring contour. The arch members are preferably formed of a flexible, resilient, sheet material such as satin or lastex having one significant direction of elasticity or stretch, the component parts 9 and 10 being cut with the direction of stretch being aligned longitudinally with the generally vertical front and back limbs 6 and 7, as illustrated by the parallel grain or stretch lines in the drawing.

The side panels 3 and 3' are attached within the arch members 4 and 4', respectively, by stitching along the innermost edge thereof. In order to grade the resilience of the sloping hip sections, crescent pieces 14 and 14', preferably formed of the same power net material as the side panels and having the direction of major stretch indicated by the grain lines, i.e., in alignment therewith, can be added to the upper portion of the side panels within the arch. The crescent pieces are attached to the innermost edges of the arch members and to the side panels so that a double thickness is provided which results in a gradation of resilience moving from the strong resilience of the side panel to the stronger resilience of the double thickness at the crescent-shaped area to the strongest resilience in the arch member. Preferably the crescent-shaped pieces are disposed against the inside surfaces of the side panels.

Fitted in the space between corresponding front limbs 6 and 6' of the arch members and secured adjacent the near edges thereof is a front panel 15 (Figure 7). The front panel 15 is preferably formed of the same power net material as the side panels 3 and 3' and the crescent pieces 14 and 14' and, in the arrangement of Figures 1-8, two layers, 15a and 15b, of fabric are used, the predominant directions of stretch being arranged on the bias or at approximately 90 degrees to each other, as shown by the stretch lines of Figure 7. The opposing bias arrangement of the weave serves to equalize the tension across the abdomen and also to distribute the forces over the abdomen in an effective figure-controlling action. In the arrangement shown by Figure 2, a waistband extension piece 16 is made part of the front panel 15, either integrally or separately. In either case, it is preferred that a curving seam 17 be included between the main panel portion and the waistband extension 16.

A waistband or collar 18, constructed in one or more pieces, is attached to the upper edge of the garment to envelope the waist to the extent required. In the event the waistband extension 16 is used on the front panel section of the waistband, joined thereto in curving seams 16a and 16b, it passes about the waist. If the extension 16 is omitted, the waistband will, of course, envelope the entire circumference of the waist. At the back of the waistband (Figure 3) an anchoring loop 18a is shown for anchoring a brassiere, for example. Other loops can be added either inside or outside the waistband for additional attachment points.

The basic assembly is completed by a back panel 19 (Figures 3 and 8), attached between the corresponding or back limbs 7 and 7' of the arch members. The back panel is preferably formed in the double layer, 19a and 19b, manner of the front panel and of the same type of material, the predominant directions of stretch being at right angles to each other and both being at angles to the horizontal and vertical. The lower portion of the back panel is intended to provide fullness, allowing the garment to go under the seat area in a sitting position. This direction of freedom does not, however, relax the girthwise control. A curved seam 19a can be included across the back panel to assist in establishing a buttocks uplift and also to establish visual continuity between the lower seams which join the crescent-shaped pieces 14 and 14' to the side panels 3 and 3'. The continuity of forces, deriving from the supporting ledges of the hips and curv-

ing rearwardly downwardly affords a sling action along the seam line beneath the buttocks. For continuity at the front of the garment, a curved seam 15a can be added to the front panel 15 to join the seams on opposite sides of the garment which secure the crescents 14 and 14'. A further and correspondingly curved seam 15b can be added between the seam 15a and the seam 16b of the waistband construction. The several curving seams impart reinforcement to the areas they traverse as well as pleasing and therefore decorative lines.

It will be understood that the invention can take various other forms and arrangements. Thus, for example, referring to Figure 10, a built-up waistband can be made by means of integral, upper extensions 20a and 21a on both the front and back panels 20 and 21, corresponding to the panels 15 and 19 of Figures 1-8. Side pieces 22 and 23 can be included between the front and back panel extensions 20a and 21a to appear above the basic side panels 24 and 25 and the arch members (not shown). Also, the directions of stretch of the several component parts can be rearranged, as illustrated by the grain or stretch lines in Figure 10, which represents a developed plan view of certain of the component parts of a complete garment. In certain cases non-stretching material can be used for certain pieces, such, for example, as the front panels 15 and 20, in which case single layers can be used.

In all cases the component parts interact to apply figure-controlling pressure to the several parts of the figure in amounts which achieve natural, pleasing contours, with the arch members 5 and 5' remaining as fixed anchors in the position of regulating the outward action of the side panels and the inward action over the abdomen and buttocks. These arch members side on the natural support ledges of the skeletal hip-bone structure to balance the interaction of movement. The arch members remain in relatively fixed positions and are contoured to rest comfortably in their positions. The non-stretch character across the limb portions of the arch members functions to prevent the center front and center back from becoming distorted on the wearer. There is a continuity of stress throughout which derives from the resilience and grains of the several materials in such manner that unusual freedom of movement obtains. The invention should not, therefore, be regarded as limited except as defined by the following claims:

I claim:

1. In a foundation garment, a pair of resilient, flexible arch members, each including an upper section laterally inclined in an oblique plane to arch over and rest on a hip of the wearer, the upper section thereby defining a contoured space to receive the hip bones, and substantially vertical front and back limbs depending therefrom, a pair of resilient, flexible side panels disposed within the respective arch members and attached to the proximate edges of the vertical limbs, and resilient, flexible front and back panels attached to the proximate edges of the vertical limbs and spanning the spaces therebetween.
2. A foundation garment as set forth in claim 1, said arch members comprising fabric having one predominate direction of stretch, said direction being arranged substantially vertically throughout the limbs and the curving upper section.
3. In a foundation garment, a pair of flexible, resilient arch members, each including an upper section to arch over and rest on a hip of the wearer and each having front and back limbs depending in a substantially vertical direction from the upper section, said limbs comprising flat bands tapered downwardly and said upper section comprising an upwardly-widening band curving into the oblique plane of the upper hip area at the top of the arch to define contoured spaces to receive the hip bones, a pair of resilient flexible side panels disposed

within and attached to the proximate edges of the limbs of the respective arch members, and resilient, flexible front and back panels attached to the proximate edges of said limbs to span the spaces between corresponding limbs of the two arch members.

4. A foundation garment as set forth in claim 3, each arch member comprising along its length at least two fabric portions joined by transverse seams and having their respective abutting ends cut at angles to impart an outward flare to the arching upper portion.

5. In a foundation garment, a pair of arch members including upper sections to arch over and rest on the respective hips of the wearer, and substantially vertical front and back limbs depending therefrom, said arch members being formed of bands of flexible, resilient sheet material, the edge of each band being convergent downwardly from the top of the arch to the bottom of the limbs, said limbs extending to the lower edge of the garment, the edges also curving out of the vertical plane over the hip areas to define contoured spaces to receive the hip bones, a pair of resilient, flexible side panels disposed within and attached to the respective arch members, and resilient, flexible front and back panels spanning the spaces between corresponding limbs of the two arch members.

6. A foundation garment as set forth in claim 5, said back panel being adapted to underlie the buttocks of the wearer, and means in the back panel to impart lift to the buttocks.

7. A foundation garment as set forth in claim 6, said means to impart lift comprising reinforcing means connected to the upper portion of the arch members and curving downwardly rearwardly in sling fashion beneath the buttocks.

8. A foundation garment as set forth in claim 5, said

material of which the arch members are formed having one predominant direction of stretch, the arch members being arranged in the garment with the direction of stretch disposed generally vertically.

5 9. A foundation garment as set forth in claim 8, said side panels being secured respectively adjacent the inner edges of the arch members, and being formed of material having major and minor directions of stretch, the major direction of stretch being disposed at an angle to the horizontal and inclining forwardly upwardly in the garment.

10 10. A foundation garment as set forth in claim 5, including waistband means above the arch members and attached thereto at the sides of the garment.

15 11. A foundation garment as set forth in claim 5, said front and back panels each comprising at least two overlying materials, having directions of stretch at angles to each other and both at angles to the horizontal, said front and back panels being attached to adjacent edges 20 of the arch members.

12. A foundation garment as set forth in claim 5, including crescent-shaped pieces at the tops of the side panels, said pieces being attached to the arching portions 25 of the arch members and to the side panels to afford a gradation of resilience from the side panels to the arch members.
